SIDE AND REAR GUARD FOR A MOTORCYCLE

Hobart Phelps, 2916 Race St., Denver, Colo.

Filed July 20, 1961, Ser. No. 65,999

Term of patent 7 years

(Cl. D90—5)

FIG. 1 is a rear perspective view of a side and rear guard of a motorcycle, showing my new design;

FIG. 2 is a side elevational view thereof; and

FIG. 3 is a top plan view thereof.

The portions of a motorcycle shown in broken lines in FIG. 2 are included for illustrative purposes only.

I claim:

The ornamental design for a side and rear guard for a motorcycle, as shown and described.
